Primary Examiner — John Windmuller(74) *Attorney, Agent, or Firm* — Morgan, Lewis & Bockius LLP(57) **CLAIM**

The ornamental design for a monitor with antenna, as shown and described.

DESCRIPTION

FIG. 1 is a front perspective view of a monitor with antenna; FIG. 2 is a front view of a monitor with antenna; FIG. 3 is rear view of a monitor with antenna; FIG. 4 is a right side view of FIG. 1; and, FIG. 5 is a left side view of FIG. 1.

The broken lines in the figures depict portions of the monitor with antenna that form no part of the claimed design.
